(57) CLAIM

The ornamental design for an automobile headlight lens, as shown and described.

DESCRIPTION

FIG. 1 is a front view of an automobile headlight lens;

FIG. 2 is a perspective left view thereof;

FIG. 3 is a back view thereof;

FIG. 4 is a side view thereof;

FIG. 5 is a top view thereof; and,

FIG. 6 is a bottom view thereof.

The broken lines are included to show environmental structure and form no part of the claimed design.

The drawings and descriptions represent the left side embodiment. The claim is also for a mirror image right side embodiment.
